Primary Examiner—Stacia Cadmus

(74) Attorney, Agent, or Firm—Kolisch Hartwell, P.C.

(57) **CLAIM**

The ornamental design for automobile console, as shown and described.

DESCRIPTION

FIG. 1 is a perspective view of the automobile console showing my design, shown in its position of use;

FIG. 2 is another perspective view of FIG. 1;

FIG. 3 is a top plan view of FIG. 1;

FIG. 4 is a bottom plan view of FIG. 1;

FIG. 5 is a side elevation view of FIG. 1;

FIG. 6 is a front elevation view of FIG. 1; and,

FIG. 7 is a rear elevation view of FIG. 1.

The console is shown on an enlarged scale in FIGS. 2-7 as compared with FIG. 1.

The broken line showing of environment is for illustrative purposes only and forms no part of the claimed design.
